Inventor

Louis J. Larsen

By his Attorney

Peter M. Dasey.

UNITED STATES PATENT OFFICE.

LOUIS JENSEN LARSEN, OF ASTORIA, NEW YORK.

METHOD OF ATTACHING SAIL SLIDES TO SAILS.

Application filed November 11, 1925. Serial No. 68,302.

This invention relates to a new and useful improvement in the method of connecting a sail slide to a sail, whereby it is possible to dispense with the use of hemp or 55
5 twine for such connection, and instead effect a more simple and stronger attachment between such parts.

Another object of my invention is to provide an inexpensive and durable device, 10 which besides being easily applicable for such purpose, and saving time and labor, also assures a rigid connection between said sail and sail-slide; features very essential in this line of manufacture.

15 With the above and other objects in view my invention consists in the novel construction, combination and arrangement of parts hereinafter fully described, reference being had to the accompanying drawing, in which 20 similar reference characters denote corresponding parts, and in which:

Figure 1 is a front elevation of an embodiment in part, of my invention; Fig. 2 is a side elevation; Fig. 3 is a transverse 25 vertical section taken on line *a—a* of Fig. 1, Fig. 4 presents a prospective view of my device unattached.

Referring in detail to the drawings, 10 designates a clip consisting of a comparatively thin strip of metal, of substantially 30 rectangular shape. This strip is formed into a clasp or clip, through a round bent 12 of its middle portion, said bent being adapted to be inserted into and secure, as a means 35 of fastening, a sail-slide 13.

Said clip has arms 11 and 11'. In order to diminish the wear and tear on the rope 14, attached to the sail 15, said arms are intermediate their ends, as at 16, provided 40 with slightly upwardly turned edges to avoid unduly friction. One arm 11 of said clip has its free end provided with an eyelet 17, adapted to receive a protuberance 18 formed on the other arm 11'. Said protuberance is cylindrically shaped and formed with a corresponding opening extending through its center.

The attachment to a sail is accomplished 45 by means of a perforation in same through 50 which is inserted said protuberance 18 to be received by the eyelet 17, whereupon the

outer edge 19 of the former by a suitable means is bent over to form a collar, making a close fitting of said two arms to the sail, as shown at 22; the sail being tightly engaged and clasped between said arms.

To avoid cutting or injuring said sail the outer edges of the arms 20, 21 are formed with a slight turning in outwardly direction, as shown in Fig. 3.

Having thus fully described my invention what I claim as new and desire to secure by Letters Patent of the United States is:

1. An article of manufacture comprising a rectangular metal body, bent upon itself and adapted to have inserted upon it a sail-slide, the arms being provided with outwardly turned edge portions, and the end portions of said arms being formed one with an eyelet and the other with a projection adapted to be received by said eyelet for the purpose of securing said arms tightly to a sail, and thereby connecting the latter to a sail-slide.

2. As an article of manufacture, a clip adapted to receive and hold a sail slide and comprising a body having arms formed therewith by bending it upon itself, slightly upwardly turned edges on said arms, intermediate the ends thereof, one of said arms having an eyelet formed near its free end, a cylindrical protuberance formed on the other arm near the free end thereof having a central opening and adapted to engage into said eyelet for attaching said arms to a sail and connecting the latter to a sail-slide.

3. As an article of manufacture, a means for attaching a sail slide to a sail, said means comprising a substantially elongated, rectangular metal body forming arms bent upon themselves and adapted to receive a sail slide, interengaging means near the outer free ends of said arms adapted to secure said body to a sail, a rope on said sail adapted to be engaged between the folded body arms, and outwardly turned edges on said arms for preventing injury to the sail when said metal body and said sail slide thereon are attached to the sail by the engagement between the interengaging means.

In testimony whereof I hereunto affix my 100 name.

LOUIS JENSEN LARSEN,
